UNITED STATES PATENT OFFICE.

CHESTER W. LARNER, OF PHILADELPHIA, PENNSYLVANIA.

OPERATING MECHANISM.

1,408,611.

Specification of Letters Patent. Patented Mar. 7, 1922.

Application filed March 9, 1918. Serial No. 221,365.

To all whom it may concern:

Be it known that I, CHESTER W. LARNER, a citizen of the United States, residing at Philadelphia, Pennsylvania, have invented 5 certain new and useful Improvements in Operating Mechanism, of which the following is a specification.

My invention relates to mechanism for operating various devices and is particularly 10 adapted for use in connection with valves of hydraulic systems. In addition to operating such devices, it is frequently necessary to operate such devices from a distance and my invention provides means for doing this and 15 at the same time indicating on the device itself its condition as to operation and also indicating at the point of control the condition of the device as to operation. To this end I provide a switch board provided with 20 one or more switches and means controlled thereby to operate the valves.

In the accompanying drawings, I have shown one form my invention may take 25 when applied to valves of hydraulic mechanism. Figure 1 shows diagrammatically a switch board. Fig. 2 is a transverse section through the switch. Fig. 3 is a horizontal section through the dotted line of Fig. 2 and Fig. 4 is a diagrammatic representation of 30 the switch and the mechanism which it controls to operate a valve.

On the switchboard shown in Fig. 1, I have shown a chart to indicate a pipe 1 having branches 2, 3 and 4 in each of which is 35 arranged one of my switches 5. Each switch 5 is provided with a slot 6 which, as will hereinafter appear, indicates by its position on the diagram on the switchboard the condition of the valve to which it corresponds. Each of the switches 5 controls a 40 valve 7 located in the hydraulic system on a pipe situated similarly to the location of the switch in the diagram on the switchboard. For instance, the switch located in the pipe 45 1 may control a valve located in the main inlet pipe of the system, and the switches located in the pipes 2 and 3 may control similarly situated valves in branches from the main pipe.

Each switch 5 consists of a base plate 8 of 50 insulating material which, in the form shown, is circular and is provided with four cavities 9 in each of which is a spring 10 surrounding the stem of a contact 11. Outside the contacts 11 and surrounding the base plate 8 is a raised margin 12. An an-

nular collar 13 also of insulating material and integral with an upwardly extending tube 14 has a bearing on the margin 12. Attached to the lower side of the collar 13 is a contact bar 15 adapted to engage and electrically connect two of the contacts 11. In the tube 14 is a diagram 16 in which is a slot 6. It will be observed that when the tube 14 is turned the contact bar 15 may be 60 caused to engage either pair of contacts 11. Below the switch 5 is permanently mounted a lamp 17 and the contact bar 15 has an opening through its center and immediately between the slot 6 and the lamp 17 so that 65 when the lamp is lighted the slot 6 will be illuminated.

In Fig. 4 I have shown one switch 5 and its associated lamp surrounded by the margin A to indicate the apparatus located 75 at the switchboard. It will be understood that there may be any suitable number of such apparatuses located on one switchboard. I have also shown the valve and the associated mechanism surrounded by the margin B to indicate the apparatus at the valve itself which may be at a distance from the switchboard. There may be any number of suitably situated apparatuses controlled from the switches of any 80 switchboard. This arrangement is particularly desirable when the operator is not so placed that he can observe the actual operation of the valves themselves but, of course, my invention will be useful when 85 there is no separation of the operator and mechanism to be operated. I have shown a valve diagrammatically at 7 arranged to be operated through a bar 18 which may be pulled toward the left by the solenoid 19 to 90 open the valve and toward the right by the solenoid 20 to close the valve. I have provided an indicator 21 pivoted at or near the valve and engaged by a pin 22 carried by the bar 18 so that the indicator moves with the 95 valve and indicates whether it is open or closed or moving from one position to the other. The indicator 21 when at the extreme left as shown in Fig. 4 engages a push button 23 and forces it, against spring 24, 100 out of contact with the contacts 25 and into engagement with the contacts 26. When the indicator 21 is moved toward the right by the closing valves it will release push button 23 opening the contacts 26 and closing the 105 contacts 25. As the valve closes and the indicator 21 reaches the right hand limit of

its movement it will engage the push button 27 supported by the spring 28, thus opening the contacts 29 and closing the contacts 30.

As shown in Fig. 4 it will be observed 5 that the circuit for the solenoid 19 is open at the contacts 25 and the circuit for the solenoid 20 is open at the contacts 11^a, 11^b and that one circuit for the lamp 17 is open at the contacts 30 while the other circuit 10 for the lamp 17 is closed at the contacts 26. The closed lamp circuit runs from the positive side of the line to the contact 11^c through the contact bar 15 and the contact 11^a through the contacts 26 to the lamp 17 15 then over to the right and up and to the negative side of the line. It will be observed that this circuit for the lamp passes through the contacts of the switch 5 so that as the switch 5 is turned to the other position 20 causing the contact bar 15 to engage the contacts 11^a and 11^b it will open the circuit through the lamp 17 and the lamp 17 will thus remain unilluminated until its other circuit is closed at the contacts 30 by the 25 final movement of the indicator 21 as the valve reaches the end of its travel.

Starting with the apparatus in the position shown in Fig. 4 the switch 5 may be moved so as to cause the contact bar 15 to engage the contacts 11^a and 11^b. This will 30 close a circuit from the positive side of the line to the contact 11^a (which is permanently connected to the contact 11^c) through the contact bar 15 to the contact 11^b to the contacts 29 through the closing solenoid 20 to the negative side of the line. This will energize the closing solenoid 20 and cause it 35 to draw the bar 18 to the right thus starting the valve toward its closing position and moving the indicator 21 out of contact with the push button 23 and allowing it to open the contacts 26 and close the contacts 25. As the valve reaches its fully closed position 40 the indicator 21 will engage the push button 27 and cause it to open the contacts 29 and close the contacts 30. This will de-energize the solenoid 20 at the contacts 29 and cause the apparatus to come to rest and at the same time close a circuit from the 45 positive side of the line through the contact 11^a and the contact bar 15 to the contact 11^b through the contacts 30 through the lamp 17 and to the right and up and to the left to the negative side of the line. It will be 50 seen thus that the switch 5 in moving de-energizes the circuit for the lamp 17 and places the slot 6 in position to indicate a new position of the valve and that the valve then proceeds to move to its new position 55 and when it finally reaches the new position the circuit for the lamp 17 is again automatically closed and the slot 6 illuminated. The switches may be arranged on the switchboard so that the slot 6 will be 60 parallel with the sides of the pipe in the 65

diagram when the switch is turned to cause the opening of its corresponding valve and so that the slot 6 is across the pipe in the diagram on the switchboard when the switch is turned to cause the valve which it controls to close. Inspection of the switchboard will indicate the position of all the valves in the system. I have shown the switches in pipes 1, 3 and 4 set to indicate the valves open. The switch shown in pipe 2 in the 70 diagram on the switchboard is shown with its slot 6 running across the pipe indicating that the valve which that switch controls is closed or being closed. As soon as a switch is turned from one position to the other the 75 corresponding light goes out and does not light again until the valve has performed the operation for which it is set. If any lamp is not illuminated it will indicate either that the valve to which it corresponds 80 is moving from one position to another or that there is something wrong with that valve or its operating mechanism because the light will not burn unless the valve operates as called for by the switch. 85 90

It will be noted that as the valve moves toward its closing position the indicator releases the push button 23 and allows the contacts 25 to close so that when the switch 5 is again turned to the position shown in 95 Fig. 4 the circuit through the opening solenoid 19 will be closed from the positive side of the line through the contact 11^c and the contacts 25 to close so that when the switch contacts 25 through the solenoid 19 and to 100 the negative side of the line.

I claim as my invention:

1. A valve, an indicator on the valve, a solenoid for opening the valve, a solenoid for closing the valve, circuits for the solenoids, contacts in the circuits, a switch for closing some of the contacts in the circuits for the solenoids, an indicator on the switch, a lamp to illuminate the indicator on the switch, circuits for the lamp, a spring supported button for opening the circuit for the opening solenoid and closing the lamp circuit and operated by the indicator on the valve when the valve opens, and a spring supported button for opening the circuit for the closing solenoid and closing the lamp circuit and operated by the indicator on the valve when the valve closes. 105 110 115

2. A device, an indicator on the device, a solenoid for moving the device in one direction, a solenoid for moving the device in the other direction, circuits for the solenoids, a switch for closing contacts in the circuits for the solenoids, an indicator on the switch, a lamp to illuminate the indicator on the switch, circuits for the lamp, a spring supported button for opening the circuit for one solenoid and closing the lamp circuit operated by the indicator on the device when the device reaches the end of 120 125 130

movement in one direction, and a spring supported button for opening the circuit for the other solenoid and closing the lamp circuit operated by the indicator on the device when the device reaches the end of movement in another direction.

3. A device, means for operating the device, a switch for controlling the means, an indicator moving with the switch to show the position of the switch and the intended position of the device, and a second switch operated by the device to deenergize the means and cause said indicator to show the arrival of the device into the intended position.

4. A switch, a device controlled thereby, an indicator moving with the device, an indicator on the switch, and means controlled by the indicator on the device for illuminating the indicator on the switch.

5. A switch, a movable device controlled thereby, an indicator moving with the switch to show the position of the switch and the intended position of the device, and means incorporated within the switch and controlled by the movement of the device for illuminating the indicator to show the arrival of the device into the intended position.

30 6. A switch, a device controlled thereby, an indicator moving with the switch to show the position of the switch and the intended position of the device, and means incorporated within the switch and controlled by the device for causing said indicator to show the arrival of the device into the intended position.

7. A device means for moving the device, a switch controlling said means, an indicator moving with the switch to show the position of the switch and the intended position of the device, and means incorporated within the switch and controlled by the device for illuminating the indicator on the switch to show the arrival of the device into the intended position.

8. A device, an indicator on the device, electrical means for operating the device, a switch for energizing the means, an indicator on the switch, a second switch operated by

the first named indicator to de-energize the means and operate the second named indicator.

9. A valve, an indicator on the valve, solenoids for operating the valve, circuits for the solenoids, a switch for closing contacts in the circuit for either solenoid, an indicator on the switch, a lamp to illuminate the indicator on the switch, circuits for the lamp, and means operated by the first named indicator for opening a solenoid circuit and closing a lamp circuit.

10. A valve, an indicator on the valve, solenoids for operating the valve, circuits for the solenoids, a switch for closing contacts in the circuit for either solenoid, an indicator on the switch, circuits for the indicator on the switch, and spring supported buttons for opening the circuits for the solenoids and closing the indicator circuits operated by the indicator on the valve.

11. A valve, an indicator on the valve, solenoids for operating the valve, circuits for the solenoids, a switch for closing contacts in the circuit for either solenoid, an indicator on the switch, a lamp to illuminate the indicator on the switch, circuits for the lamp, and spring supported buttons for opening a lamp circuit and then opening a solenoid circuit and closing a lamp circuit operated by the indicator on the valve when the valve operates.

12. A device, a switch controlling the device, an indicator moving with the switch to indicate the controlled position of the device, and means incorporated within the switch for illuminating the indicator only when the device has reached the controlled position.

13. A device, means for moving the device, a diagram, a switch in the diagram corresponding to the device and controlling the moving means, an indicator moving with the switch and showing by its position on the diagram the position of the device for which the switch is set, and means controlled by the device for causing the indicator to show the arrival of the device into the position for which the switch is set.

CHESTER W. LARNER.
